UNITED STATES PATENT OFFICE.

THOMAS BOND, SR., OF DALLAS, TEXAS, ASSIGNOR OF ONE-HALF TO
FREDERICK J. PAGEL, OF DALLAS, TEXAS.

REIN-HOLDER.

SPECIFICATION forming part of Letters Patent No. 778,167, dated December 20, 1904.

Application filed May 23, 1904. Serial No. 209,419.

To all whom it may concern:

Be it known that I, THOMAS BOND, Sr., a citizen of the United States, residing at Dallas, in the county of Dallas and State of Texas, have 5 invented new and useful Improvements in Rein-Holders, of which the following is a specification.

The invention relates to improvements in rein-holders.

10 The object of the present invention is to improve the construction of rein-holders and to provide a simple, inexpensive, and efficient one of great strength and durability adapted to be readily applied to the dashboard of a 15 vehicle for holding the reins when the driver leaves the vehicle.

A further object of the invention is to provide a device of this character which will be in convenient position for enabling the reins 20 to be quickly engaged with it and removed from it without crossing them and which will hold the reins at opposite sides of the center of the dashboard, so that when they are 25 grasped for removing them from the device they will be in position for driving.

With these and other objects in view the invention consists in the construction and novel combination and arrangement of parts hereinafter fully described, illustrated in the accompanying drawings, and pointed out in the 30 claim hereto appended, it being understood that various changes in the form, proportion, size, and minor details of construction within the scope of the claim may be resorted to without departing from the spirit or sacrificing any of the advantages of the invention.

In the drawings, Figure 1 is an elevation of a rein-holder constructed in accordance with this invention and shown applied to a 40 dashboard. Fig. 2 is a longitudinal sectional view of the device. Fig. 3 is a transverse sectional view. Fig. 4 is a detail perspective view of the resilient upper clamping plate or piece. Fig. 5 is a similar view of the lower 45 plate.

Like numerals of reference designate corresponding parts in all the figures of the drawings.

1 designates a dash rod or rail arranged above

a dashboard 2 in the usual position and connected with the said dashboard by clips 3 of the ordinary construction. The dash-rail supports the rein-holder and enables the same to be readily applied to a dashboard; but the rein-holder, which comprises a lower fixed clamping-plate 4 and an upper resilient clamping-plate 5, may be applied to the dashboard in any other desired manner. The lower clamping-plate 4, which in practice is preferably welded to the dash rod or rail 1, is provided with a lower 50 concaved face 6 to conform to the configuration of the same, and it may be secured thereto by any other means. The plate or piece 4, which is provided with a central recess or seat 7, has longitudinal corrugations 8 at opposite sides of the same. These corrugations form projecting ribs, which are adapted to engage the lines to prevent the same from slipping through the device.

The seat or recess 7 receives a lug or enlargement 9 of the upper resilient clamping plate or spring 5, which is secured to the lower clamping-plate by means of a screw 10 or other suitable fastening device. By this construction the upper clamping-plate 5 is interlocked with the lower clamping-plate 4 and is thereby spaced therefrom and at the same time prevented from turning. The central depending lug or enlargement 9 is slightly tapered, as shown, and it supports the upper 70 clamping plate or spring above the lower clamping-plate, as clearly illustrated in Figs. 1 and 2 of the drawings. The lower clamping-plate is provided with a central threaded opening for the reception of the screw, and 75 this opening 12 is preferably extended into the rod or rail 1, as indicated in Fig. 2. The ends 13 of the upper clamping-plate are curved upward and outward, as shown, and the end edges 14 of the lower clamping-plate are bevelled to provide a flaring mouth or entrance at each end of the rein-holder to permit the reins 80 to be readily inserted between the clamping-plates.

The reins are adapted to be readily introduced into the device by sliding them inwardly under the upper resilient clamping-plate, and they will be securely held in this position at 95

opposite sides of the center of the dashboard in convenient position to be readily grasped by the driver for removing them from the device. When the driver grasps the reins for 5 removing them from the rein-holder, they are in proper position for driving and the reins are not crossed in introducing them into and removing them from the device.

Having thus fully described my invention, 10 what I claim as new, and desire to secure by Letters Patent, is—

In a rein-holder, the combination with a dash-rail, of a lower clamping-plate grooved at its lower face to receive and fit the rail and 15 provided at its upper face between its ends with a recess and having longitudinal corrugations located at opposite sides of the recess for engaging the reins, the ends of the plate

being beveled, an upper resilient clamping-plate provided with a depending lug fitting 20 in the recess of the lower clamping-plate and spacing the plates from each other and also interlocking them, the ends of the upper plate being extended beyond the lower plate and upwardly curved, and a fastening device 25 piercing the upper and lower clamping-plates and engaging the dash-rail and securing the parts together.

In testimony that I claim the foregoing as my own I have hereto affixed my signature in 30 the presence of two witnesses.

TOM. BOND, SR.
